UNITED STATES PATENT OFFICE.

FREDERICK LAW OLMS TED, OF BROOKLINE, AND JAMES W. BASTON, OF ARLINGTON,
MASSACHUSETTS; SAID BASTON ASSIGNOR TO SAID OLMS TED.

ABRADING-CYLINDER.

1,070,284.

Specification of Letters Patent. Patented Aug. 12, 1913.

Application filed March 1, 1911. Serial No. 611,682.

To all whom it may concern:

Be it known that we, FREDERICK LAW OLMS TED, a citizen of the United States, and resident of Brookline, county of Norfolk, State of Massachusetts, and JAMES W. BASTON, a citizen of the United States, and resident of Arlington, county of Middlesex, State of Massachusetts, have invented an improvement in Abrading-Cylinders, of which the following description, in connection with the accompanying drawing, is a specification, like characters on the drawing representing like parts.

This invention has for its object the production of a novel and efficient abrading cylinder of simple and durable construction for use in pencil sharpening machines, or the like or in any grinding or polishing machines.

One of the important features of the invention is the provision whereby a continuous strip or roll of abrasive material, such as flint or garnet paper, or other abrasive medium of suitable character, may be used, a portion thereof being held by suitable means in operative position upon the exterior of a rotatable cylindrical carrier. When the exposed portion of the abrading strip is worn a fresh portion is pulled from the supply in reserve and the worn portion is torn off.

The various novel features of the invention will be fully described in the subjoined specification and particularly pointed out in the following claims.

Figure 1 is a side elevation of the rotatable carrier, with the rolled strip of abrading material in place and having its free end carried around and clamped upon the periphery of the carrier, the latter being viewed from its open end; Fig. 2 is a view principally in section on the line 4—4, Fig. 1, looking toward the left; Fig. 3 is an enlarged sectional detail through the cylindrical wall of the carrier, taken on the line 5—5, Fig. 2.

The carrier for the abrading medium will now be described.

Referring to Fig. 2, a strong stud 26 is screwed into the threaded hole in the block 11 and held tight by a check-nut 27, the stud extending horizontally through a suitable hole in the channel-plate 7 and having rotatably mounted upon it the internal hub 28 of a hollow or chambered carrier

comprising a circular inner end 29 and a cylindrical wall 30. Said carrier is conveniently a metal casting, the outer end of its hub being counterbored to receive the head 31 of the stud 26, whereby the carrier is retained upon the latter. A portion of the periphery of the carrier is provided with worm-teeth 32 which mesh with and rotate a gear secured to the pencil-holder when the carrier is used in a pencil sharpening machine, rotation being effected by means of a suitable handle 33, Fig. 1, carried on a radial ear 34 extended from the wall 30 at the open end of the carrier.

A transverse, slotted seat 35 is made in the cylindrical wall 30 of the carrier, extending from the open end thereof to a longitudinal slot 36, see Fig. 2, adjacent the series of gear teeth 32. The wall 30 is thickened at one side of the seat, as at 37, Fig. 3, and the beveled face 38 of the thickened part forms one side of the seat, a rock-shaft 39 being sustained in a transverse hole in the part 37 parallel to the axis of rotation of the carrier. Attached to the ends of the rock-shaft are inwardly extended, L-shaped arms 40, to which are pivotally connected at 41 rigid legs 42 secured to or forming part of a flat and rather thin clamp 43 which is adapted to be drawn into the slotted seat 35 or moved outward therefrom, when the rock-shaft is turned in one or the other direction. One of the arms 40 and the connected clamp leg 42 swing in the longitudinal slot 36 in the carrier wall, while the other arm and its connected leg swing free at the outer or open end of the carrier, as will be apparent from Fig. 2.

A strip of abrading material, such as flint or garnet paper, or similar abrasive medium, or any polishing medium is used in this invention, the strip being of such width that it will pass easily between the clamp legs 42 and of such length that after being passed around the periphery of the carrier a considerable surplus remains. This abrading strip is preferably wound in roll form, as at 44, upon a suitable spool 45 adapted to be easily pushed onto the end of the carrier hub 28, with the roll inside the carrier, as shown. The free end of the strip is passed through the slotted seat 35, between the clamp legs, and over the beveled face 38, and then it is carried around the periphery of the carrier, as at 46, the free

end 47 being passed under the clamp 43 and overlapped upon the portion lying on the face 38, see Fig. 3. After the part of the abrading strip embracing the periphery of the carrier is pulled taut the clamp 43 is drawn into the seat 35, pinching the interposed abrading strip between the clamp and the seat proper which latter is slightly flared and shallow at its outer end. The abrading strip is thus clamped securely in its operative position upon the periphery of the carrier, as will be clearly understood, and if the end 47 is too long it is torn off, using the adjacent side of the clamp as a straight-edge.

The arm 40 at the open end of the carrier has an extension 48 provided at its free end with an enlargement 49 having a segmental slot 50 through which is passed the threaded shank of a locking nut 51, the shank being screwed into a hole 52 in the end of the hub 28, Fig. 2.

As will be apparent from Fig. 1 the farther to the left the extension 48 is swung the tighter will the clamp 43 be drawn inward to clamp the abrading strip in the seat provided therefor, and the clamp is locked in its operative position by setting up the nut 51. A positive, unyielding yet adjustable locking device is thus provided for the clamp. As the slotted end 49 of the extension 48 is clamped against the outer end of the hub 28 the roll 44 of abrading material is held in place within the carrier, as shown in Figs. 1 and 2, the extension being swung upward to the right and the locking nut 51 being removed from the hub when a fresh roll is to be placed in the carrier. When the exposed portion of the abrading strip has been worn down to such an extent that it will no longer perform its proper function the clamp 43 is released, the free or exposed end 47 of the strip is grasped, and by pulling the same longitudinally the worn part of the strip is drawn off and a fresh part from the roll is pulled out of the carrier and around its periphery. After the clamp has been locked upon the seat the long end of the used strip is torn off across the edge of the clamp and the machine is ready for use. Obviously the outer face of the clamp makes a break in the abrading surface, but it is in the arc of the latter and narrow, and no objectionable effects result.

Various changes or modifications in details of construction and arrangement may be made by those skilled in the art without departing from the spirit and scope of the present invention as set forth in the claims hereunto annexed.

Having fully described our invention, what we claim as new and desire to secure by Letters Patent is:

1. In a device of the class described, the combination with a hollow, rotatable carrier

having a cylindrical wall provided with a transverse, slotted seat, of a long strip-like abrading member encircling the said wall of the carrier and passing through the seat into the interior of the carrier to form a reserve supply, and a manually governed clamp to hold upon the seat the ends of the exposed portion of such abrading member.

2. In a device of the class described, the combination with a hollow, rotatable carrier having a cylindrical wall adapted to operatively sustain an encircling portion of an elongated abrading strip, said wall having a transverse, slotted seat for the passage into the carrier of the surplus portion of the abrading strip, a clamp pivotally connected at its ends with said wall and adapted to clamp upon the seat the adjacent ends of the exposed part of the abrading strip, and adjustable, positively acting means to lock the clamp in operative position.

3. In a device of the class described, a hollow, rotatable carrier having a cylindrical wall adapted to sustain an encircling portion of an elongated abrading strip, said wall having a transverse, slotted seat for the passage into the carrier of the surplus portion of the abrading strip, and adjustable means to clamp upon the seat the adjacent ends of the exposed portion of the strip.

4. In a device of the class described, in combination, a hollow, rotatable cylindrical carrier having a transversely slotted periphery adapted to sustain a surrounding strip of abrading material and to hold within it a continuous reserve portion of the strip passed through the slot, and means to positively clamp the overlapped portions of the strip against the walls of the slot.

5. In a device of the class described, in combination, a cylindrical, rotatable carrier open at one end and having an interior hub, the periphery of the carrier having a transverse slotted seat therein, an external clamp adapted to enter said seat and fulcrumed on the carrier, and means to lock the clamp in the seat upon portions of a strip of abrading material embracing the periphery of the carrier, the surplus length of the strip passing through the seat into the interior of the carrier and being supported upon the hub.

6. In a device of the class described, in combination, a rotatable, cylindrical carrier open at one end for the reception of an abrading strip in roll form and having a central hub to support such roll, the circular wall of the carrier having a transverse, slotted seat for the passage therethrough of the free end of the abrading strip, the latter encircling and being supported by the circular wall, a clamp fulcrumed upon the carrier and adapted to clamp upon the seat the overlapped parts of the exposed part of the abrading strip, a controlling member connected with the

clamp, and means to lock said member when the clamp is in operative position.

7. In a device of the class described, in combination, a rotatable, cylindrical carrier open at one end and having a transverse, slotted seat in its periphery, a clamp to enter said seat, arms connected with the clamp and pivotally mounted in the circular wall of the carrier adjacent the seat, and locking means connected with one of the arms, to hold the clamp positively in the seat.

8. In a device of the class described, the combination, with a hollow, rotatable carrier having a cylindrical wall adapted to operatively sustain an encircling portion of an elongated abrading strip, said wall having a transverse, slotted seat for the passage into the carrier of the surplus portion of the abrading strip, a clamp, arms pivotally connected therewith and fulcrumed in the cylindrical wall of the carrier adjacent the seat, an extension on one of said arms, and means to lock said extension from movement when the clamp has been moved to clamping position in the seat.

9. In a device of the class described, in combination, a cylindrical, rotatable carrier open at one end and having an interior hub,

the periphery of the carrier having a transverse slotted seat therein, an external clamp 30 adapted to enter said seat and fulcrumed on the carrier, a locking extension at the open end of the carrier operatively connected with and to swing said clamp into and out of the seat, the free end of the extension 35 having a segmental slot therein, and a locking nut having its shank passed through the slot and screwed into the outer end of the carrier hub, to lock said extension and the clamp with the latter operatively positioned 40 in the peripheral seat of said carrier.

10. An abrading cylinder comprising a rotatable cylindrical carrier having a transverse slotted seat in its periphery, a clamp to enter said seat, a lever connected with 45 the clamp and pivotally mounted on the carrier and means for securing the parts in adjusted position.

In testimony whereof, we have signed our names to this specification in the presence of two subscribing witnesses.
